UNITED STATES PATENT OFFICE

2,488,462

STAPLING MACHINE ATTACHMENT

Morris A. Zucker, New York, N. Y.

Application June 27, 1947, Serial No. 757,574

4 Claims. (Cl. 1—3)

1

This invention relates to an attachment for button or ornament applying machines.

An object of this invention is to provide an attachment for button machines which will permit the attaching of pronged buttons or ornaments to fabric and also secure ornamental cords, braids or tapes to the fabric.

Another object of this invention is to provide a device of this kind which will permit rapid operation of the machine, and which includes a lower die so formed and constructed as to releasably hold the button prior to the crimping of the prongs.

A further object of this invention is to provide an attachment of this kind which includes a guide extending laterally of the machine and attached at its inner end to the machine, and a die carrying slide engages the guide, the slide being gravity urged by means of a weight to an inner operative position. A pivoted handle is carried by the slide for shifting the slide laterally to loading position against the pull of the weight, and dropping of the handle downwardly at the outer end of the guide will cause the handle to lock the slide in its loading position.

A further object of this invention is to provide a device of this kind which includes interchangeable guides for the tape or yarn, the guides being either of single or multiple construction so that one or more strands of yarn or tape may be attached to the fabric.

With the above and other objects in view, my invention consists in the arrangement, combination and details of construction disclosed in the drawings and specification, and then more particularly pointed out in the appended claims.

In the drawings,

Figure 1 is a detail front elevation of a button attachment constructed according to an embodiment of this invention.

Figure 2 is a plan view of the attachment with the button machine partly broken away.

Figure 3 is a detail and elevation of the attachment.

Figure 4 is a fragmentary sectional view taken on the line 4—4 of Figure 1.

Figure 5 is a fragmentary sectional view taken on the line 5—5 of Figure 3.

Figure 6 is a fragmentary sectional view taken on the line 6—6 of Figure 5.

Figure 7 is a fragmentary vertical section of the lower die member.

Figure 8 is a plan view of the yarn guide.

Figure 9 is a plan view, partly broken away, of a ribbon guide.

2

Figure 10 is a fragmentary plan view showing a piece of yarn secured by pronged buttons to a fabric, according to this invention; and

Figure 11 is a fragmentary plan view of a piece of fabric showing a plurality of strands secured thereto by means of elongated or bar-shaped buttons.

Referring to the drawings, the numeral 15 designates generally a frame of a conventional button machine which includes a horizontal lower frame member 16 and an upper arm 17 disposed in parallel relation with the lower member 16 and connected thereto by means of a connecting member 18.

15 The forward end of the arm 17 is formed with a bushing 19 through which a vertical slidable shaft 20 engages. The shaft 20 in the present instance has mounted on the upper end thereof a knob 21 and a spring 22 constantly urges the shaft 20 upwardly to inoperative position.

An upper die or clinching member 23 is detachably secured to the lower end of the shaft 20 and is adapted to overturn the prongs of a button as will be hereinafter described. A lower die member generally designated as 24 is disposed 25 when in operative position in confronting position with respect to the upper die or clinching member 23. The lower die member 24 comprises a vertically disposed stud 25 formed at its upper end with a button seat 26.

30 The stud 25 has integral therewith a collar 27 and a button retaining sleeve 28 is slidable on the stud 25. The sleeve 28 includes an enlarged bushing 29 formed with a flange 30 at its upper end. A spring 31 is interposed between the flange 30 and the lower collar 27. The stud 25 at a point between the ends thereof is formed with a slot or elongated recess 32 within which a set screw 33 loosely engages so as to limit the vertical movement of the bushing 29 and the sleeve 28.

35 The sleeve 28 is adapted to normally be disposed partly above the upper end of the stud 25 so that the prongs 34 of a button or ornament 35 will be substantially entirely disposed within the area of the extended portion of the sleeve 28, as shown in Figure 7.

The stud 25 also includes a lower stud member 25a extending below the collar 27 and adapted 50 to be secured by means of a fastening device 36 in a bushing 37 disposed in upstanding position on the upper side of a horizontal slidable sliding member 38. The slide member 38 is slidably carried by a horizontally disposed stationary guide 39 which is formed of an elongated bar 40 and

3

guide forming strips 41 fixed by fastening members 42 to the bar 40. The guide bar 39 at its inner end portion has fixed thereto a depending stud 43 which is adapted to engage in the outer end of the frame member 16, and a set screw 44 is threaded through the outer end of the horizontal frame member 16 and secures the stud 43 against rotary movement.

The bar 40 is also braced against horizontal swinging movement by means of a bracing bar mounted on one end on a set screw and secured at the opposite end to a screw 46 threaded into the bar 40. A spacer sleeve 47 is adapted to be interposed between the outer end of the frame member 16 and the bar 45 so that this latter bar will be disposed on the desired bracing angle to prevent horizontal swinging of the guide member 39.

In order to provide for automatic inward movement of the slide 38 to position the lower die member 24 in operative position, I have provided a weight 48 which has secured thereto a flexible member 49. The flexible member 49 is secured at the opposite end thereof to a pin 50 carried by the slide member 38. A pulley 51 is rotatably carried by a horizontally extending bracket or arm 52 which is fixed to the inner end of the guide member 39.

The slide member 38 is adapted to be moved laterally to the right and inoperative or loading position by means of a handle 53 pivotally carried by a pair of upwardly extending ears 54 fixed to the outer end of the slide 38. The handle 53 is adapted, as shown in Figure 1, to bear against the outer end of the guide 39 so as to thereby lock the slide 38 against inward movement during the time that the lower die 24 is being loaded.

After a new button, nailhead, pronged fastener has been placed within the sleeve 28, the handle 53 is raised to disengage the handle from the end of the guide 39 and the weight 48 will then gravitatingly pull the slide 38 inwardly until the inner end of the slide 38 abuts against the bracket 52. At this time the lower die 24 will be disposed in alignment and confronting position with respect to the movable die or clinching member 23.

A horizontally disposed table 55 is disposed above the frame member 16 and is formed at its outer end with a right angle plate 56. A vertically disposed supporting plate 57 is secured by fastening members 58 to the outer edge of the guide bar 40 and the plate 57 is provided with elongated slots 59 so that plate 57 may be horizontally adjusted. The plate 57 is also provided with a pair of vertical elongated slots 60 through which fastening member 61 engage so that the table 55 may be vertically adjusted to the desired degree.

A yarn guiding member generally designated as 62 is disposed below the table 55 and comprises an elongated bar 63 having a plurality of sideways abutting tubes 64 secured thereto.

The front plate 56 is formed with an elongated opening 65 through which the tubular guide members 64 are exposed, and the inner ends of these tubular guide members 64 terminate short of the sleeve 28. At least one strand of yarn 66 is adapted to be extended through one of the guide members 65 and a piece of fabric 67 is adapted to engage over the table 55.

The table 55 is formed with a relatively large opening 68 and when the upper die or clinching member 23 is moved downwardly to clinch the prongs 34 of the button 35, the prongs 34 will pierce the yarn 66 and also pierce the fabric 67 which at this time will be forced downwardly.

4

through the large opening 68. The secured yarn will then pass upwardly through the opening 68 on the upper side of the table 55.

The upper side of the fabric 67 which will be the inner side of the fabric when applied to a garment or the like, may be suitably marked such as with a pencil or stencil to indicate the exact positions of the buttons to be secured thereto. The guide supporting bar 63 is formed with openings 69 adjacent to the opposite ends thereof and fastening members 70 are adapted to secure the supporting bar 63 to the lower side of the table 55. The guide 62 may be adjusted lengthwise of the table 55 through the provision of elongated slots 71 formed in the table 55.

Referring to Figure 9, there is disclosed a modified form of guide 62a which includes an elongated supporting bar 63a and a flat guide tube 64a fixed to the bar 63a. The flat tube 64a is designed for guiding a ribbon or the like beneath the table. It will be understood that there may be two or more of these flat guide members 64a depending on the number of ribbons to be attached by each button.

In the use and operation of this device, the attachment is secured to the button frame by inserting the stud 43 in the outer end of the button frame and securing the stud by means of the set screw 44. In loading the lower die 24, the slide 38 is moved to the right until the handle 53 drops downwardly against the rear end of the guide 39. The button may then be inserted in the inverted position within the sleeve 28 of the lower die 24. The fabric is placed on top of the table 55 and the yarn or other material which is to be secured to the fabric is inserted through the guides 64 and 64a.

The handle 53 is then raised upwardly so that the weight 48 will pull the slide 38 inwardly to operative position. The upper movable die or clinching member 23 may then be moved downwardly, pressing the fabric 67 downwardly through the opening 68 and clinching the prongs 34 through the yarn or decorative material to the fabric 67. The fabric may then be moved inwardly, pulling therewith the yarn or decorative material, and the slide then moved outwardly by means of the handle 53 to its reloading position.

With an attachment of this kind, any desired decorative buttons may be easily and quickly secured to the fabric, and decorative strand material or ribbons may also be secured through the medium of the buttons to the fabric.

The term "button" as herein used is defined as a pronged element which may be of any desired shape and size. It will be understood that the upper and lower dies will be shaped in a manner to conform to the particular shape of the button which is being secured to the fabric, and that a single button may be used to secure one or more strands or ribbons or combinations thereof to the fabric.

I do not mean to confine myself to the exact details of construction herein disclosed, but claim all variations falling within the purview of the appended claims.

What I claim is:

1. In a button machine having a frame and an upper movable clinching member; an attachment 70 comprising a horizontally disposed guide member, means mounting said guide member on said frame, a slide carried by said guide, a button supporting member carried by said slide, means constantly urging said slide to a position whereby 75 said lower member will be disposed in alignment

with said upper clinching member, a combined slide shifter and lock carried by said slide adapted upon lateral shifting of said slide from a clinching position to a lateral loading position to engage the outer end of said guide and thereby hold said slide against inward movement, and means for supporting and guiding material between said die members.

2. An attachment for a button machine having a C-shaped frame formed with horizontally disposed upper and lower arms and an upper movable clinching member, said attachment comprising an elongated guide, means mounting said guide on said lower arm at substantially right angles to the latter, a slide carried by said guide, an upstanding lower die member carried by said slide adjacent the inner end of said slide, weight means constantly urging said slide inwardly to position said die member in alignment and in clinching position, means for moving said slide laterally to loading position, means for holding said slide in loading position, and means supporting fabric in operative position with respect to said die member.

3. An attachment for a button machine having a C-shaped frame formed with horizontally disposed upper and lower arms and an upper movable clinching member, said attachment comprising an elongated guide, means mounting said guide on said lower arm at substantially right angles to the latter, a slide carried by said guide, an upstanding lower die member carried by said slide adjacent the inner end of said slide, weight means constantly urging said slide inwardly to position said die members in alignment and in clinching position, means for moving said slide

laterally to loading position, means for holding said slide in loading position, a material supporting table carried by said guide, and tubular material guiding means carried by said table for locating one of the materials to be joined with respect to the lower die and clinching member.

4. An attachment for a button machine having a C-shaped frame formed with horizontally disposed upper and lower arms and an upper movable clinching member mounted on the free end of said upper arm, said attachment comprising an elongated guide, means mounting said guide on said lower arm at substantially right angles to the latter, a slide carried by said guide, an upstanding lower die member carried by said slide adjacent the inner end of said slide, weight means constantly urging said slide inwardly to position said die members in alignment and in clinching position, means for moving said slide laterally to loading position, means for holding said slide in loading position, a material supporting table carried by said guide, tubular material guiding means carried by said table, and means adjustably supporting said table from said guide.
